NATHAN J. STRAUSS, OF LYNBROOK, NEW YORK, ASSIGNOR, BY DIRECT AND MESNE ASSIGNMENTS, OF ONE-THIRD TO FREYDBERG BROS., INC., OF NEW YORK, N. Y., A CORPORATION OF NEW YORK, AND TWO-THIRDS TO JOSEPH SILBERMAN AND LOUIS KAHN, TRADING AS RESISTO MANUFACTURING COMPANY, OF BALTIMORE, MARYLAND.

TIE, TIE PIECE GOODS, AND METHOD OF MAKING

Application filed May 17, 1926. Serial No. 109,648.

This invention is an improvement in ties and has particular reference to wholly or partly lined ties, and to the method of connecting the lining to the body material of the tie.

Ties of silk and like goods are formed from blanks which are cut from piece goods, the blanks usually being in two pieces, for several reasons, among which may be mentioned the 10 narrow widths in which such goods are usually supplied, and to insure the matching of the pattern at the ends of the tie when lying along side each other. The two pieces are connected at about the middle of the tie, and 15 the blank is folded into tubular form, and the edges of the blank are turned over onto the rear face and usually lapped along the middle line of the tie, forming thus a tubular structure.

20 In all ties, a lining is provided of suitable material, which is loosely held in the tubular tie formation, as by basting, so that relative movement between the tubular formation of the body material and the lining material is 25 facilitated, thus to prevent as far as possible distortion or deformation of the body material by drawing of the lining.

When the rear face of the body material is of a suitable character, the lining may be 30 omitted at the ends of the tie, the back or inner face of the body material providing a suitable ornamental display at these points. Where the back of the body material is not of a suitable character, the lining is extended to 35 the ends of the tie, but in either case it is practically impossible by usual methods to connect the lining in a manner such that it will not become displaced in usage.

It is impractical to connect the lining to the 40 body by stitching the edges of lining and body together prior to folding. A smooth fold without rumpling would be difficult to attain, and the edge of the lining would not offer a firm support to the edge of the tie, and 45 moreover would be extremely liable to displacement, thus causing the tie to sag or break down at the edge.

A primary object of the present invention is the provision of a tie material, including a 50 body and a lining secured together through-

out the extent of the contacting area of the elements.

Another object is the provision of a tie, wherein the lining is made into what is substantially an integral part thereof, being 55 secured to the body material of the tie throughout the extent thereof.

Another object is the provision of a tie material having a lining so connected to the body material that a blank may be folded into 60 the form of a tie without wrinkling or rumpling of either body or lining.

Another object is the provision of a tie material from which a blank may be cut 65 having a lining secured to the body throughout the area of the lining, and leaving a part of the body material exposed.

Another object is the provision of a tie material from which blanks may be cut having a lining secured to the body throughout 70 the extent of the lining and so arranged that the hidden parts of the lining may be of cheaper material than the exposed parts.

Another object is the provision of a tie material having a lining covering all or a part of the rear or inner face of the material, and secured thereto throughout the area thereof, and of a character such that a tie 75 may be completed by turning over the edges of a blank onto the rear face thereof and cementing the edges to the blank.

Another object is the provision of a method of forming a tie wholly or partially lined and with the lining substantially an integral 80 part of the body material.

With these and other objects in view the invention consists in the construction and novel combination of parts fully described hereinafter, illustrated in the accompanying drawings, and pointed out in the claims appended hereto, it being understood that various changes in the form, proportion, size and minor details of construction within the scope of the claims, may be resorted to without departing from the spirit of the invention.

In the drawings:

Fig. 1 is a plan view looking from the back of a section of the improved tie material, with a blank separated therefrom.

Fig. 2 is a rear view of the completed tie. Fig. 3 is a section on the line 3—3 of Fig. 2. Fig. 4 is a view similar to Fig. 1 of an alternate construction.

Fig. 5 is a partial plan view looking from the rear of a formed tie made from the material shown in Fig. 4.

The tie material shown in Fig. 1 includes a body material 1 of a suitable character, as for instance silk, and a lining 2 of any suitable nature, preferably harmonizing with the body material, and providing an ornamental surface for the rear or inner face of such material. The lining is secured to the body material throughout the area of the lining, and the lining may be coextensive with the body material as shown in Fig. 1, or it may cover only a part thereof as in Fig. 4.

The lining is secured to the body material by means of rubber cement indicated at 3. The surfaces of body material and lining to be joined are both treated with a coating of the cement, which is applied in any suitable manner. The elements of the tie material, that is the body material and the lining are then superposed, and pressed firmly together in any suitable manner. Thus the parts are firmly united throughout the area of the contacting surface, so that the body material and lining constitute what is in effect an integral structure.

The blanks for the tie are usually cut on the bias, in the manner indicated at 4 in Fig. 1, the reference character indicating one section of the cut blank. Because of the narrow widths in which such goods are supplied and to insure matching of the pattern at the ends when lying along side each other, the tie blanks are usually in two pieces, each piece constituting about one-half the tie. It will be evident from the description that each blank in the Fig. 1 construction is composed of a layer of body material, and a layer of lining coextensive therewith, and firmly secured thereto throughout the entire area of the contacting surfaces.

To form the tie, the two pieces of the blank are united, after which the side edges of the blank are folded over upon the body, as indicated at 5 and 6 in Figs. 2 and 3. The fold 6 which is outermost has the edge turned in between the fold and the fold 5 as indicated at 7, and the folds 5 and 6 are secured together in a suitable manner, as for instance by stitches 8.

So made, the tie is a structure wherein the lining is closely and intimately united with the body material throughout the area of the tie, so that there is no possibility of relative displacement, and the structure is such that there is little possibility of wrinkling in usage.

In some cases, and especially in ties of a tubular formation, the lining is only visible at the ends of the tie as shown in Fig. 2.

In such cases, it may not be desired to provide a tie with a relatively expensive lining throughout its extent, in which case the material may be prepared as shown in Fig. 4.

In this instance the body material 9 of the tie is provided with a composite lining, composed of a central portion 10, and side portions 11. The portion 10 which covers the greater part of the body material may be of a relatively inexpensive nature, or where additional stiffness or body is desired, it may be of a material suitable to serve either or both purposes. The side portions 11 are of goods of a higher grade and of a more ornamental character, as for instance silk or the like.

The portion 10 occupies the center of the width of body material, with a strip 11 on each side, each strip 11 being of a width somewhat greater than the length of the portion of the lining which will be exposed in the completed tie.

The portions 10 and 11 are joined to the body material 9 in the same manner as the lining 2 is joined to the body 1 in Fig. 1. That is the rear face of the body material is coated with the rubber cement. The faces of the portions 10 and 11 to be united to the body are similarly coated, and superposed onto the body material. By heavy pressure the lining portions and the body are firmly connected. In practice a portion of each strip 11 will lap upon the portion 10, thelapping indicated at 12 in Fig. 4, and this lapping portion is usually free from the portion 10, although it is obvious that it may be secured thereto if desired.

In cutting the tie material into blanks, the patterns are so arranged that the pieces of the blanks alternate. The wide end of one piece is at one side edge of the piece goods, while the wide end of the complementary piece is at the other side. This attains economy of the material, and also insures that the pattern will correspond at the ends of the tie, when the said ends lie along side each other. In order to enable the usual method of cutting, it is advisable to arrange the lining portions 10 and 11 as shown in Fig. 4, even though in the completed blank there is a strip of relatively expensive lining material at the center of the tie which is hidden within the tubular structure of the completed tie.

The pieces of the blank 13 are cut from the material of Fig. 4, in such manner that the large end of each piece is cut from a strip 11 and the adjacent part of the body material. When now the blank is folded into the tubular formation, the lapping folds 14 and 15 will conceal all of the lining except portions of strip 11, which is as before stated of an ornamental nature. Otherwise the tie is constructed the same as that shown in Fig. 2.

In ties made from goods wherein the rear or inner face of the material is sufficiently ornamental for display, the tie may be constructed by omitting the strips 11. That is the entire lining will be constituted by the portion 10 leaving a strip of the body material at each edge unlined. When now the blank is folded, it will be evident that at the ends of the tie the rear or inner face of the body material will be visible, while the lining will be hidden within the tubular structure.

Instead of a tubular structure, with lapping folds directly connected, the tie may be constructed by turning over the edges of the blank a short distance like a hem and connecting them by bar tacking, that is, connecting the spaced folds or edges across the body of the tie. With this construction, a saving of body material is effected.

It will be obvious that with a tie material of a character such that there is no necessity to match pattern at the ends of the tie when lying alongside each other, the blank might be a unitary structure, in which case the material could be made as shown in Fig. 1, or as shown in Fig. 4, or it could be made with merely the lining portion 10. One of the substantial advantages of the improved tie is that the united lining forms a firm reinforce or support for the edges of the tie where sagging or breaking down first takes place.

Another striking advantage of the construction is that a relatively light and cheap body material, when lined as specified, has the feel and appearance of a much heavier and more expensive material.

What is claimed as new is:

1. A necktie, composed of a face piece, a back piece, and an elastic adhesive material interposed between the two pieces and intimately uniting the same throughout the area of the pieces falling within the knot-tying portion of the tie, said three parts being resilient longitudinally.

2. A necktie, composed of a face fabric, a back fabric, and an elastic adhesive material interposed between said two fabrics and intimately uniting the same throughout their contacting areas, said three parts being resilient longitudinally.

3. A necktie, composed of a face piece, a back piece, and an elastic adhesive material interposed between the two pieces and intimately uniting the same throughout the width of the tie in the knot-tying portion thereof, said three parts being resilient longitudinally.

4. A necktie, comprising a face piece of longitudinally resilient fabric, and a backing of resilient material adhesively secured to the fabric throughout the area of its knot-tying portion.

5. A necktie, comprising a face piece of

longitudinally resilient material, and an adhesive backing of elastic material adhesively secured to the back of the face piece and extending throughout the area of the face piece.

Signed at New York in the county of New York and State of New York this 12th day of May, A. D. 1926.

NATHAN J. STRAUSS.
